UNITED STATES PATENT OFFICE

172,231

PLATE

Alexander E. Lewis, Brooklyn, N. Y.

Application November 24, 1953, Serial No. 27,777

Term of patent 14 years

(Cl. D44—15)

To all whom it may concern:

Be it known that I, Alexander E. Lewis, a citizen of the United States and a resident of Brooklyn, New York, have invented a new, original, and ornamental Design for a Plate, of which the following is a specification, reference being had to the accompanying drawing, forming a part hereof.

The figure is a top plan view of a plate showing my new design.

The plate is of conventional configuration.

I claim:

The ornamental design for a plate, substantially as shown and described.
